UNITED STATES PATENT OFFICE.

ABRAM M. ROOS, OF KINGSTON, NEW YORK.

NON-REFILLABLE BOTTLE.

SPECIFICATION forming part of Letters Patent No. 683,989, dated October 8, 1901.

Application filed February 11, 1901. Serial No. 46,762. (No model.)

To all whom it may concern:

Be it known that I, ABRAM M. ROOS, a citizen of the United States, residing at Kingston, in the county of Ulster and State of New York, have invented certain new and useful Improvements in Non-Refillable Bottles, of which the following is a specification.

My invention has relation to a bottle, and particularly to the stopple or valve device therefor for rendering such a bottle of a non-refillable type or kind, and in such connection it relates to the construction and arrangement of the devices in the bottle for the said purpose.

15 The principle object of my invention is to provide a bottle with a stopple or valve device mounted in the neck of the bottle and so arranged as to permit of the contents of the bottle being readily discharged by inverting or tilting the same, and a bottle in which further use is prevented or refilling of the same rendered impossible without destroying or mutilating certain parts connected with the stopple or valve device mounted in the neck of the bottle.

20 My invention, stated in general terms, consists of a non-refillable bottle when constructed and arranged in substantially the manner hereinafter described and claimed.

25 The nature and characteristic features of my invention will be more fully understood from the following description, taken in connection with the accompanying drawings, forming part hereof, in which—

30 Figure 1 is a vertical central sectional view of the neck and upper portion of a bottle, showing a stopple or valve device mounted in a bottle embodying the main features of my invention and showing the valve in its normally-closed condition when the bottle is occupying an upright position. Fig. 2 is a similar view of the neck of a bottle with my invention mounted therein and with the perforated valve in an inverted position in its chamber for permitting of the discharge of the fluid contents from the bottle when the latter occupies a turned upside-down position; and Fig. 3 is a perspective view of the perforated valve and its perforated sleeve or 35 stem detached from its chamber, which is adapted to be mounted in a packing or cork

housing in the neck of the bottle, as illustrated, for example, in Figs. 1 and 2.

Referring to the drawings, A is the bottle in broken section and provided with a neck a. 55 B is the valve-chamber, being a part of the valve of my present invention, and provided with the upper outlet b' from the bottle and lower tubular inlet b to the bottle. This chamber, with its inlet, is mounted in the neck a in a packing of cork or other preferred material b² and the outlet b' of the chamber B is held and surrounded by a cork or similar ring b³, the whole engaging the recessed portion a' of the interior surface of the neck a 60 of the bottle, as clearly illustrated in Figs. 1 and 2 of the drawings.

c is a band spanning the exterior surface of the neck a of the bottle and provided with spurs or tacks c', extending through openings 70 provided in the neck a of the bottle into the body of the ring b³ and arranged so that the band or the like c must be mutilated or destroyed by removal of the spurs or tacks c' before the bottle can again be used for filling 75 with a fluid substance or other preferred material.

B' is a weighted cup-shaped valve with a hollow perforated stem movably fitting into the chamber B and with its stem afforded a 80 play up and down in the inlet b to the bottle. This valve B' in a sidewise or preferably a downward movement of the bottle, as illustrated in Fig. 2, will permit of the contents of the bottle flowing through the hollow stem 85 of the valve and the series of apertures d, provided therein, into the body of the chamber around the main body of the valve B' and outward through the outlet b' of the valve-chamber B into the upper portion of the neck 90 of the bottle and therefrom into any suitable receptacle to receive the same. It may be here remarked that if the bottle be again caused to assume the position illustrated in Fig. 1 and a fluid poured into the neck of the 95 bottle the same will flow through the outlet b' of the chamber B and fill the cup-shaped valve B' and flow over the same into the chamber B until it has become filled, but without any of the fluid finding its way into the bottle, 100 because access thereto is shut off by the weight of the fluid bearing down on the valve

in its chamber and confining tightly the hollow stem of the said valve B' in its chamber or inlet b of the chamber B to the bottle, thereby preventing refilling of the bottle 5 without removing the band c, surrounding the neck of the bottle, and along therewith the spurs or tacks c', engaging through the openings of the neck the packing-ring or body b³, surrounding the hollow tubular outlet b' 10 of the valve-chamber B from the bottle, and removing then the said ring or body along with the valve-chamber B and its packing b³.

Having thus described the nature and object of my invention, what I claim as new, and 15 desire to secure by Letters Patent, is—

1. A non - refillable bottle, comprising a valve-chamber provided with an inlet and an outlet and mounted in a packing in the neck of the bottle and a cup-shaped valve provided 20 with recesses or openings in the upper portion and said valve mounted in said chamber provided with a hollow stem having openings therein, and securing means extending through the neck of said bottle into the packing within the neck thereof, substantially as and for the purposes described. 25

2. A non-refillable bottle, comprising a tubular valve-chamber provided with a tubular inlet and a tubular outlet and mounted in 30 a suitable packing in the neck of the bottle, a cup-shaped valve provided with semicircular recesses or openings in the upper portion mounted in said chamber, a hollow stem with openings therein mounted in the inlet of said 35 chamber to the bottle, and a band surrounding the neck of the bottle and provided with

spurs or tacks extending through the neck of the bottle and into the packing within the neck of said bottle, substantially as and for the purposes described. 40

3. A non-refillable bottle provided with a valve-chamber having a body portion and upper and lower tubular portions suitably held in a packing in the neck of the bottle, a weighted cup-shaped valve with a semicircular recessed upper edge and a tubular barrel or stem having a series of openings extending therethrough, said valve mounted in the body of said chamber and said barrel or stem engaging in the lower tubular portion of said chamber, a band surrounding the neck of said bottle, and securing means extending through said band on the neck of the bottle and into the packing within the neck thereof, substantially as and for the purposes described. 45

4. A non-refillable bottle provided with a weighted cup-shaped valve with a perforated stem mounted in a complementary chamber provided with a tubular barrel in packing recessed into the neck of the bottle and a band 50 spanning the neck of said bottle with securing means extending through the bottle into said packing, substantially as and for the purposes described.

In testimony whereof I have hereunto set 65 my signature in the presence of two subscribing witnesses.

ABRAM M. ROOS.
